[57] **CLAIM**

The ornamental design for a dual lock for bicycles,
motorcycles, as shown and described.

DESCRIPTION

FIG. 1 is a top plan view of a dual lock for bicycles,
motorcycles showing my new design;

FIG. 2 is a front elevational view thereof;

FIG. 3 is a bottom plan view thereof;

FIG. 4 is a left side elevational view thereof;

FIG. 5 is a right side elevational view thereof; and,

FIG. 6 is a rear elevational view thereof.

The broken lines in FIGS. 1 and 2 representing a steering
column of a bicycle are for illustrative purposes
only and form no part of the claimed design.

FIG. 1

FIG. 2

FIG. 5

FIG. 3

FIG. 4

FIG. 6
